PROCESS FOR MAKING ANHYDRIDES

Lino Rigon, Melle, France, assignor to Les Usines
de Melle (Societe Anonyme), Saint-Leger-les-
Melle, France, a corporation of France

Application June 28, 1950, Serial No. 170,714

Claims priority, application France July 15, 1949

11 Claims. (Cl. 260—546)

1
This invention relates to a process for making aliphatic anhydrides. More particularly, it relates to a continuous process for the production of lower aliphatic anhydrides—by which expression I mean anhydrides which have from 4 to 8 carbon atoms—such as acetic anhydride, but without limitation, by direct oxidation with a gas containing molecular oxygen of the corresponding aldehydes.

The principal object of the invention is to provide a simple, efficient process of the kind described to produce a high yield of anhydride at a low cost of operation and employing simple apparatus.

The invention accordingly comprises the novel processes and steps of processes, specific embodiments of which are described hereinafter by way of example and in accordance with which I now prefer to practice the invention.

I have found in accordance with my invention that I may achieve the above objects by continuously introducing a gas containing molecular oxygen, and a lower aliphatic aldehyde such as acetaldehyde, but without limitation, into a liquid bath containing the following ingredients: The aldehyde to be oxidized, the corresponding acid, the acetic or other anhydride to be produced, and metallic salts capable of acting as aldehyde oxidation catalyst. The bath also contains one or more diluents having a boiling point above 200° C. The diluent is present in the proportion of at least 75% of the total weight of the bath and is chemically inert to the other ingredients thereof and to the oxygen-containing gas at temperatures required for oxidation of the aldehyde into anhydride and at such temperatures remains liquid. The diluent is also insoluble in and does not dissolve water and is miscible with the anhydride to be produced and the corresponding acid. The mixtures of the aforementioned ingredients are such as to be able to dissolve the catalyst in the required proportions for the oxidation reaction. Diluents having such properties are referred to in the appended claims as "inert diluents." The proportions of the ingredients are such that the bath is not of too high viscosity to interfere with efficient contact between gas and liquid. Under such conditions, when aldehyde and the oxygen containing gas are introduced into the bath, anhydride is produced and there is no substantial combination of water with the formed anhydride to impair the yield of anhydride. Under the conditions of my process, it is also unnecessary to return diluent or anhydride con-

tinuously to the liquid oxidation bath. Of course, it should be understood that instead of using a single aldehyde, there may be used two aldehydes simultaneously if it is desired to obtain a mixed anhydride of the kind

The diluents mentioned above have a low degree of volatility. They increase considerably the relative volatility of the water in the oxidation bath and, being present in the high proportion of at least three-fourths of the bath, cause the water to be carried away as it is formed by the gas stream passing through the bath, the diluent itself remaining in the bath.

As it is not compulsory for the auxiliary substances used as diluents in accordance with this invention to assume another function, generally more important than that of the diluent, the disadvantages which would result from the assuming of more than one function by the auxiliary substances do not occur.

The proportion of diluent or mixture of diluents answering the above requirements will be preferably of 75% to 90% of the total weight of the bath.

There is no upper limit regarding the boiling point of the diluent or mixture of diluents, provided that it is in the liquid form while in operation and that its viscosity is not too high which would result in a less efficient contact between gas and liquid.

Furthermore, I have found that, among the substances meeting the above requirements, esters of any kind are particularly suitable, said esters being formed either by mineral acids, or aliphatic or aromatic organic acids, such acids being monobasic or polybasic, reacted with monobasic or polybasic alcohols or phenols.

The oxidation reaction is carried out at a temperature in the range 40–100° C., according to the kind of anhydride to be produced; for instance, temperature must be higher for making butyric anhydride from butyraldehyde than for making acetic anhydride from acetaldehyde.

The catalysts to be employed are preferably metallic salts, more particularly salts of polyvalent metals (such as cobalt, nickel, copper, vanadium) and an acid such as acetic acid corresponding to the anhydride to be produced; however, other metallic salts, such as silver salts, may also be used; all these salts may be employed either separately or in mixtures, at a concentration of from 0.1 to 1%, preferably from 0.2 to 0.4%, of the weight of the bath.

The oxidizing gas may be air or another mixture of oxygen with an inert gas such as CO₂, CH₄, etc. . . . ; according to an embodiment of this invention, at least part of the gases that have been passed through the bath and thereafter cooled, may be returned to the bath and reintroduced thereinto; in admixture with fresh oxidation gas or oxygen.

Another characteristic of this invention is that the partial pressure of oxygen in the gases that are introduced into the oxidation bath must be, as much as possible, lower than 76 mm. Hg, preferably between 23 and 60 mm. Hg, which corresponds, when the operation is carried out at atmospheric pressure, to a proportion of oxygen lower than 10%, preferably between 3 and 8% by volume. Formation of peroxides, such as peracetic acid, is thus avoided, therefore risks of explosion are reduced. Furthermore, higher yields are secured since, the oxidation being less intensive, the proportion of by-products resulting either from decomposition of the unstable peroxides, or directly from the oxidation of the starting aldehyde, is reduced.

I have further found that it is advisable to maintain the concentration of aldehyde in the oxidation bath below about 5% by weight, but not below about 0.3%. In practice, the concentration of aldehyde will be maintained between about 1 and about 2% of the weight of the bath.

It is preferable that the gases and vapors escaping from the bath be cooled at a temperature not exceeding 15° C. approximately, at least part of the uncondensed gases being returned to the oxidation apparatus. The rate of flow of the gases may, with advantage, be of 1 to 3 cubic meters, preferably 1.8 to 2.5 cubic meters, per hour per liter of bath.

The operation may be carried out either at atmospheric pressure or at a higher or lower pressure.

The process of this invention may be advantageously be executed in the following manner, using the apparatus diagrammatically represented in the appended drawing which is not limitative.

The aldehyde to be oxidized, for example, acetaldehyde, is continuously supplied through pipe 2 to a cylindrical reaction vessel 1 provided with adequate means for putting gases into intimate contact with liquids; a porous plate for example. The heat evolved by the reaction is removed by any means whatever, for example, an external cooling device 4 through which a portion of the oxidation bath contained in vessel 1 is continuously circulated by pump 3. Pipe 26 permits the introduction into vessel 1 of the diluent and of the catalysts.

The oxidizing gases are introduced through pipe 13 and, after having given the aldehyde part of their oxygen, escape through pipe 5 while carrying away both the reaction products (anhydride, acid, water) and part of the unconverted aldehyde. Then, the gases pass successively through two condensers 6 and 7 cooled by means of water and brine, respectively. The greatest part of the entrained vapors is condensed, then separated from the residual gases in separation chamber 8. A liquid is obtained which consists of acetic anhydride, acetic acid, water and aldehyde. From this material, the acetic or other anhydride is separated and recovered by known means; as, for example, that described in United States Patent No. 2,159,146.

After separation from the condensed liquid in chamber 8, the residual gases escape from sepa-

ration chamber 8 through pipe 10 and are divided into two parts; the greatest part flows through pipe 11 and is returned to vessel 1 by blower 12 and pipe 13; the other part, corresponding to the discharge of an amount of nitrogen (or other inert gas) equal to that supplied during the same time as oxygen-containing gas, which discharge is necessary for keeping the desired proportion of oxygen in the circulating gaseous mixture, is directed through pipe 14 into washing column 15 in which it is scrubbed by a solvent which preferably is the same substance as the diluent supplied to vessel 1 at the start, but may be another substance such, for example, as the same anhydride as that to be obtained, or the corresponding acid, or a high boiling ester other than the diluent, or generally any suitable solvent whatever, the use of which cannot interfere with the process. The scrubbing solvent dissolves the aldehyde, acid and anhydride that may have remained in the gases after condensation, and the gases, completely freed from the vapors they were carrying, escape into the atmosphere through pipe 16.

The solvent flowing out of column 15 is sent into heat exchanger 18, then into heater 19, then into column 20. At the foot of column 20, fresh air (or other oxygen-containing gas) intended to keep the desired concentration of oxygen in the circulating gaseous mixture, is introduced through pipe 21. This oxygen-containing gas in column 20 becomes laden with the products dissolved by the solvent in column 15, and is then sent through pipe 22 into the oxidizing gaseous cycle; preferably into pipe 11.

The solvent, freed from aldehyde, acid and anhydride, flows out of column 20 through a pipe 23 at the foot thereof, and is sent by pump 24 into the heat exchanger 18 where it gives its heat to the solvent flowing out of column 15, then passes into cooler 25 where it is brought to a temperature suitable for the scrubbing, and then goes into column 15 through pipe 17.

The following are examples of my process as I now prefer to practice it. It is to be understood that these examples are illustrative of the invention and that the invention is not to be considered as restricted thereto except as indicated in the appended claims.

Examples

1. I introduced into the reaction vessel: 80 kgs. of butyl benzoate, 16 kgs. of acetic anhydride, 4 kgs. of acetic acid in which have been dissolved: 55 500 grams of cobalt acetate, 100 grams of copper acetate, and 50 grams of nickel acetate, and 1.5 kgs. of acetaldehyde.

This mixture was brought to 55° C., and a stream of air was introduced thereinto, at the rate of 25 cubic meters per hour. As soon as the oxidation reaction began (this fact is recognizable by the rise in the temperature of the bath, which has to be cooled down to keep the temperature at 55° C.), acetaldehyde was fed at the rate of 20.5 kgs. per hour. The reaction products carried by the residual gases were condensed by means of cooling until their temperature was brought down to 5° C. and were separated, and part of the residual gases was returned to the oxidation vessel and circulated through the cycle, as above described, at the rate of 125 cubic meters per hour.

The equilibrium being attained, the concentration of oxygen in the gases introduced into the bath remained equal to 7% by volume, and the

concentrations of the components of the bath, equal to the starting concentrations.

I then ascertained that the condensate as obtained in separation chamber 8 had the following composition:

	Per cent by weight
Acetic anhydride	56
Acetic acid	22.2
Water	10
Acetaldehyde	11.8

This composition corresponds to a transformation rate of 84% of the starting aldehyde; the anhydride yield was 75% of the oxidized aldehyde.

2. I introduced into the reaction vessel:

78 kgs. of dimethyl phthalate,
20 kgs. of acetic anhydride,
2 kgs. of acetic acid,
2 kgs. of acetaldehyde,
200 grams of cobalt acetate, and
20 grams of silver acetate.

The operation was conducted as in Example 1, the numerical data being as follows:

Temperature of the bath 55° C.
Air supply 20 cubic meters per hr.
Acetaldehyde supply 15 kgs. per hour.

Residual gases returned to the 145 cubic meters per hr. vessel.

Concentration of oxygen in the 8% by volume, gases introduced into the bath.

Temperature in condenser 7 5° C.

Condensate as obtained in chamber 8:

Acetic anhydride 57% by weight,
Acetic acid 20% by weight,
Water 10.2% by weight,
Acetaldehyde 12.8% by weight.

Transformation rate 83% of the aldehyde used.

Anhydride yield 77% of the oxidized aldehyde.

3. Mixture in the reaction vessel:

84 kgs. of dibutyl phthalate,
18 kgs. of acetic anhydride,
2 kgs. of acetic acid,
1 kg. of acetaldehyde,
50 grams of cobalt acetate, and
500 grams of copper acetate.

The operation was conducted as in Example 1, the numerical data being as follows:

Temperature of the bath 50° C.
Air supply 10 cubic meters per hr.
Acetaldehyde supply 8 kgs. per hour.

Residual gases returned to the 160 cubic meters per hr. vessel.

Concentration of oxygen in the 7.5% by volume, gases introduced into the bath.

Temperature in condenser 7 5° C.

Condensate as obtained in chamber 8:

Acetic anhydride 54.8% by weight,
Acetic acid 17.5% by weight,
Water 9.7% by weight,
Acetaldehyde 18% by weight.

Transformation rate 77% of the aldehyde used.

Anhydride yield 78.6% of the oxidized aldehyde.

4. Mixture in the reaction vessel:

80 kgs. of allyl benzoate,
17 kgs. of acetic anhydride,
4 kgs. of acetic acid,
1.5 kgs. of acetaldehyde,
100 grams of cobalt acetate,
100 grams of copper acetate, and
20 grams of silver acetate.

The operation was conducted as in Example 1, the numerical data being as follows:

Temperature of the bath 53° C.
Air supply 20 cubic meters per hr.
Acetaldehyde supply 15.5 kgs. per hour.

Residual gases returned to the 180 cubic meters per hr. vessel.

Concentration of oxygen in the 6% by volume, gases introduced into the bath.

Temperature in condenser 7 10° C.

Condensate as obtained in chamber 8:

Acetic anhydride 64% by weight,

Acetic acid 16.2% by weight,

Water 11.5% by weight,

Acetaldehyde 8.3% by weight,

Transformation rate 89% of the starting aldehyde.

Anhydride yield 82.5% of the oxidized aldehyde.

5. Mixture in the reaction vessel:

85 kgs. of amyl benzoate,

12 kgs. of acetic anhydride,

2 kgs. of acetic acid,

1 kg. of acetaldehyde,

100 grams of cobalt acetate, and

200 grams of copper acetate.

The operation was conducted as in Example 1, the numerical data being as follows:

Temperature of the bath 54° C.

Air supply 15 cubic meters per hr.

Acetaldehyde supply 13 kgs. per hour.

Residual gases returned to the 230 cubic meters per hr. vessel.

Concentration of oxygen in the 5% by volume, gases introduced into the bath.

Transformation rate 80% of the starting aldehyde.

Anhydride yield 88% of the oxidized aldehyde.

6. Mixture in the reaction vessel:

75 kgs. of dibutyl maleate,

23 kgs. of acetic anhydride,

1 kg. of acetic acid,

1 kg. of acetaldehyde,

100 grams of cobalt acetate, and

50 grams of copper acetate.

The operation was conducted as in Example 1, the numerical data being as follows:

Temperature of the bath 52° C.

Pressure 250 mm. Hg.

Air supply 50 cubic meters (calculated at atmospheric pressure) per hour.

Acetaldehyde supply 7.5 kgs. per hour.

No residual gases are returned to the vessel.

Partial pressure of oxygen in 53 mm. Hg. the gases introduced into the bath.

Transformation rate 40% of the starting aldehyde.

Anhydride yield 80% of the oxidized aldehyde.

7. Mixture in the reaction vessel:

85 kgs. of butyl stearate,

13 kgs. of acetic anhydride,

1 kg. of acetic acid,

1 kg. of acetaldehyde,

80 grams of cobalt acetate,

150 grams of copper acetate, and

20 grams of silver acetate.

The operation was conducted as in Example 1, the numerical data being as follows:

Temperature of the bath 53° C.

Pressure 1 kg. (above atmospheric pressure) per sq. cm.

Air supply 20 cubic meters (calculated at atmospheric pressure) per hour.

Acetaldehyde supply (about) 16 kgs. per hour.

Residual gases returned to the 240 cubic meters (at a relative pressure of 1 kg. per sq. cm.) per hour.

Concentration of oxygen in the 3% by volume, gases introduced into the bath.

Transformation rate 95% of the starting aldehyde.

Anhydride yield 79% of the oxidized aldehyde.

8. Mixture in the reaction vessel:

75 kgs. of glycerol tributylate,
22 kgs. of acetic anhydride,
1.5 kgs. of acetic acid,
1.5 kgs. of acetaldehyde,
120 grams of cobalt acetate,
80 grams of nickel acetate, and
100 grams of copper acetate.

The operation was conducted as in Example 1, 10 the numerical data being as follows:

Temperature of the bath 50° C.
Air supply 25 cubic meters per hr.
Acetaldehyde supply 21.5 kgs. per hour.
Residual gases returned to the 225 cubic meters per hr. vessel.
Concentration of oxygen in the 6% by volume. 15 gases introduced into the bath.
Transformation rate 80% of the starting aldehyde.
Anhydride yield 85% of the oxidized aldehyde.

9. Mixture in the reaction vessel:

80 kgs. of tributyl phosphate,
17 kgs. of acetic anhydride,
2 kgs. of acetic acid,
1 kg. of acetaldehyde,
50 grams of silver acetate,
100 grams of nickel acetate, and
100 grams of copper acetate.

The operation was conducted as in Example 1, 30 the numerical data being as follows:

Temperature of the bath 55° C.
Air supply 20 cubic meters per hr.
Acetaldehyde supply 18 kgs. per hour.
Residual gases returned to the 240 cubic meters per hr. vessel.
Concentration of oxygen in the 4% by volume. 35 gases introduced into the bath.
Transformation rate 82% of the starting aldehyde.
Anhydride yield 90% of the oxidized aldehyde.

In this operation, acetic acid was used as a solvent for washing the residual gases before their being discarded, instead of using the same ester as is employed as a diluent in the bath, viz. tributyl phosphate. 45

10. Mixture in the reaction vessel:

42 kgs. of ortho-tolyl benzoate,
42 kgs. of tributyl borate,
18 kgs. of acetic anhydride,
2 kgs. of acetic acid,
1 kg. of acetaldehyde,
50 grams of cobalt acetate, and
500 grams of copper acetate.

The operation was conducted as in Example 1, 55 the numerical data being as follows:

Temperature of the bath 50° C.
Air supply 10 cubic meters per hr.
Acetaldehyde supply 8 kgs. per hour.
Residual gases returned to the 160 cubic meters per hr. vessel.
Concentration of oxygen in the 9% by volume. 60 gases introduced into the bath.
Transformation rate 68% of the aldehyde used.
Anhydride yield 75% of the oxidized aldehyde.

11. The operation was carried out under the same conditions as in Example 4, tetrahydrofuryl benzoate being substituted for allyl benzoate, and the results were substantially the same.

12. The operation was carried out under the same conditions as in Example 4, citronellyl acetate being substituted for allyl benzoate, and the results were substantially the same.

13. The operation was carried out under the same conditions as in Example 9, ethyl phenyl-

acetate being substituted for tributyl phosphate, and the results were substantially the same.

14. The operation was carried out under the same conditions as in Example 9, diethyl dibromomalonate being substituted for tributyl phosphate, and the results were substantially the same.

15. Mixture in the reaction vessel:

60 kgs. of ortho-diethyl phthalate,
16 kgs. of glycerol triacetate,
22 kgs. of butyric anhydride,
2 kgs. of butyric acid,
1.2 kgs. of butyraldehyde,
200 grams of copper acetate, and
100 grams of cobalt acetate.

The operation was conducted as in Example 1, the numerical data being as follows:

Temperature of the bath 90° C.
Air supply 19 cubic meters per hr.
Butyraldehyde supply 23.5 kgs. per hour.
Residual gases returned to the 161 cubic meters per hr. vessel.
Concentration of oxygen in the 6% by volume. 20 gases introduced into the bath.
Temperature in condenser 7 15° C.
Condensate as obtained in chamber 8:
Butyric anhydride 75% by weight.
Butyric acid 8.65% by weight.
Water 8.55% by weight.
Butyraldehyde 7.8% by weight.
Transformation rate 90.8% of the starting aldehyde.
Anhydride yield 90.5% of the oxidized aldehyde.

In this operation, butyric anhydride was used as a solvent for washing the residual gases, instead of using the same esters as are employed as diluents in the bath, viz. ortho-diethyl phthalate and glycerol triacetate.

16. Mixture in the reaction vessel:

40 78 kgs. of ortho-diheptyl phthalate,
19.5 kgs. of propionic anhydride,
2.5 kgs. of propionic acid,
1.4 kgs. of propionaldehyde,
180 grams of copper propionate, and
180 grams of cobalt propionate.

The operation was conducted as in Example 1, the numerical data being as follows:

Temperature of the bath 65° C.
Air supply 15 cubic meters per hr.
Propionaldehyde supply 15 kgs. per hour.
Residual gases returned to the 150 cubic meters per hr. vessel.
Concentration of oxygen in the 6.8% by volume. 50 gases introduced into the bath.
Temperature in condenser 7 12° C.
Condensate as obtained in chamber 8:
Propionic anhydride 66% by weight.
Propionic acid 13.7% by weight.
Water 9.1% by weight.
Propionaldehyde 11.2% by weight.
Transformation rate 86% of the starting aldehyde.
Anhydride yield 84.6% of the oxidized aldehyde.

17. Mixture in the reaction vessel:

77 kgs. of ortho-dimethyl phthalate,
11 kgs. of aceto-butyric anhydride

8 kgs. of butyric anhydride,
3.5 kgs. of acetic anhydride,
1.7 kgs. of butyric acid,
0.8 kg. of acetic acid,
1.1 kgs. of butyraldehyde,
0.5 kg. of acetaldehyde,
100 grams of copper acetate, and
140 grams of cobalt butyrate.

The operation was conducted as in Example 1, the numerical data being as follows:

Temperature of the bath	60° C.
Air supply	20 cubic meters per hr.
Aldehyde supply (equimolecular mixture of butyraldehyde and acetaldehyde).	20.35 kgs. per hour, comprising: Butyraldehyde, 12.6 kgs. Acetaldehyde, 7.75 kgs.
Residual gases returned to the vessel.	180 cubic meters per hr.
Concentration of oxygen in the gases introduced into the bath.	5.8% by volume.
Temperature in condenser 7	10° C.
Condensate as obtained in chamber 8:	
Aceto-butyric anhydride	62.4% by weight.
Butyric anhydride	5.45% by weight.
Acetic anhydride	10.1% by weight.
Butyric acid	1.55% by weight.
Acetic acid	0.95% by weight.
Water	11.05% by weight.
Butyraldehyde	4.1% by weight.
Acetaldehyde	4.4% by weight.
Transformation rates	91% of the starting butyraldehyde. 87.5% of the starting acetaldehyde.

Total anhydride yield	97% of the oxidized aldehydes.
Relative proportions of the obtained anhydrides:	
Aceto-butyric anhydride	80% by weight.

Butyric anhydride 7% by weight.
Acetic anhydride 13% by weight.

It is remarkable that when mixed anhydrides, such as aceto-butyric anhydride, are prepared in accordance with my process, the yield of mixed anhydride is substantially higher with respect to the total yield of the corresponding simple anhydrides produced at the same time, such as butyric and acetic anhydrides, than in processes used heretofore for preparing such mixed anhydrides.

18. Although the esters are the preferred diluents to be employed in accordance with my invention, this invention is not limited thereto and other substances answering the mentioned requirements may be used as diluents, giving excellent results. As an example, there will be described thereafter an operation using a higher acid anhydride as a diluent.

Mixture in the reaction vessel:

78 kgs. of octanoic anhydride,
19 kgs. of acetic anhydride,
3 kgs. of acetic acid,
1.35 kgs. of acetaldehyde,
200 grams of copper acetate,
50 grams of cobalt acetate, and
50 grams of silver acetate.

The operation was conducted as in Example 1, the numerical data being as follows:

Temperature of the bath	54° C.
Air supply	16 cubic meters per hr.
Acetaldehyde supply	13.6 kgs. per hour.
Residual gases returned to the vessel.	124 cubic meters per hr.
Concentration of oxygen in the gases introduced into the bath.	5.2% by volume.
Temperature in condenser 7	13° C.
Transformation rate	85% of the starting aldehyde.
Anhydride yield	77.8% of the oxidized aldehyde.

For sake of convenience and brevity, the term "aldehyde" appearing in the appended claims is intended to be a generic term representing a single aldehyde as is employed for making a simple anhydride, as well as two aldehydes employed simultaneously as this is the case when a mixed anhydride is to be obtained. Likewise, the term "acid" appearing in the claims is intended to represent, in the case where one aldehyde is used the corresponding acid, and in the case

where two aldehydes are used the corresponding acids. Likewise, the term "anhydride" appearing in the claims is intended to represent either one simple anhydride in the case where one aldehyde is used, and in the case where two aldehydes are used, the mixture consisting of the mixed anhydride and the two simple anhydrides resulting from oxidation of the two aldehydes.

What I claim is:

- 10 1. A process which comprises, continuously introducing a gas containing molecular oxygen, and aliphatic aldehyde having from 2 to 4 carbon atoms, into a liquid bath containing aldehyde to be oxidized, the corresponding acid, the anhydride corresponding to said acid, metallic salts capable of acting as aldehyde oxidation catalyst and at least 75% of the total weight of said liquid bath of an inert diluent selected from the group consisting of an ester and an anhydride having a boiling point above 200° C. and mixtures of said ester and anhydride, which diluent is insoluble in and does not dissolve water, is miscible with the anhydride to be produced as well as with the corresponding acid and when mixed with such acid and anhydride, such mixture is capable of dissolving the catalytic salts in the proportion required for catalysis of the reaction between the aldehyde and oxygen, and oxidizing such aldehyde at a temperature of about 40-100° C. to produce the corresponding anhydride, the partial pressure of said oxygen being lower than 76 mm. of mercury, said gas being introduced at a rate such that the residual gas removes from the bath substantially all of the anhydride, acid and water formed, while the diluent remains in the bath.
- 15 2. A process in accordance with claim 1 employing an inert ester and upon oxidizing the aldehyde removing the gases from the bath, cooling said gases to separate anhydride therefrom and returning part of the gases directly to the bath.
- 20 3. A process in accordance with claim 2 which includes cooling the gases at a temperature not substantially above 15° C., separating anhydride therefrom and subjecting the remainder of the gas, after return of uncondensed gases to the bath, to washing with a solvent to recover any valuable solute contained therein.
- 25 4. A process in accordance with claim 3 in which the washing is done by a circulating solvent which is of the same character as said diluent passing through a cycle including a first zone for washing the residual uncondensed gases and a second zone for extracting the valuable substances therefrom, in which second zone the solvent containing said substances is put into contact with fresh gas containing molecular oxygen flowing towards the oxidation bath so that such gas carries such recovered valuable substances and as such is introduced into said bath.
- 30 5. A process according to claim 4 in which the solvent circulating through the cycle is subjected to variations of temperature so as to be relatively cold for washing the residual gases and relatively warm for extraction of the valuable substances therefrom.
- 35 6. A process according to claim 3 in which the solvent is the same substance as is used as a diluent in the oxidation bath.
- 40 7. A process in accordance with claim 1, in which said diluent is an ester formed from an acid and a hydroxy-compound, said acid being selected from the class consisting of monobasic and polybasic inorganic and organic acids, said hydroxy-compound being selected from the

11

classes consisting of monobasic and polybasic alcohols and phenols.

8. A process in accordance with claim 7 in which the aldehyde is acetaldehyde and acetic anhydride is produced.

9. A process in accordance with claim 7 in which the bath contains by weight 75% to 90% of diluent.

10. A process in accordance with claim 7 in which the partial pressure of oxygen in the 10 oxygen-containing gas is between 23 and 60 mm. of mercury, said gas being supplied to the bath at the rate of about 1 to 3 cubic meters per hour per liter of bath.

11. A process in accordance with claim 7 in 15

12

which concentration of aldehyde in the bath is maintained at about 0.3 to 5% by weight of said bath.

LINO RIGON.
